UNITED STATES PATENT OFFICE.

ARTHUR W. KROON, OF GLENELLYN, ILLINOIS.

GATE.

1,328,168.

Specification of Letters Patent. Patented Jan. 13, 1920.

Application filed April 19, 1917, Serial No. 163,172. Renewed November 13, 1919. Serial No. 337,386.

To all whom it may concern:

Be it known that I, ARTHUR W. KROON, a citizen of the United States, residing at Glenellyn, in the county of Cook and State 5 of Illinois, have invented new and useful Improvements in Gates, of which the following is a specification.

This invention relates to farm and other gates, and its object is to provide a strong 10 and durable gate which is so constructed, braced and hung that it is effectually prevented from sagging.

The object stated is attained by means 15 of a novel combination and arrangement of parts to be hereinafter described and claimed, and in order that the same may be better understood, reference is had to the accompanying drawing forming a part of this specification.

20 In the drawing a perspective view of the gate is shown.

The gate is made up of longitudinal top and bottom rails 5 and 6, respectively, vertical end rails 7 and 8, respectively, intermediate vertical rails 9, a diagonal brace bar 10 extending between the end rails, and diagonal brace bars 11 extending between the end rails and the adjacent intermediate 25 vertical rails. These parts may be made of wood or metal firmly fastened together, and they may also be wired up to prevent the 30 passage of small stock. The vertical end bars and the intermediate bars are arranged in pairs, and the top and bottom bars, as well 35 as the brace bars, are secured therebetween.

The gate is hinged to a post 12 by suitable 40 hinges 13 the coacting members of which are fastened to the post 12 and to the end rail 7, respectively.

To prevent the gate from sagging the following system of braces is provided:

The intermediate vertical rail 9 next to the end rail 7 rises a short distance from the top rail 5 to form a strut which carries at 45 its upper end an eye 14 to which are connected brace or tie members 15 and 16, re-

spectively, which may be chains, cables or other suitable devices.

On the top of the hinge post 12 is fastened a bracket member 17 supporting an up- 50 standing pivot pin 18 on which is mounted, to turn freely thereon, a hinge member 19. One end of the brace 15 is connected to the eye 14 and the other end is connected to the member 19. The brace 15 is provided with 55 a turnbuckle 20 or other suitable tensioning device. The pivot 18 is in alinement with the axis of the hinges 13 of the gate.

At the top of the gate, adjacent to the forward end thereof, is secured a hook 21. 60 One end of the brace 16 is attached to this hook and the other end is attached to the eye 14. The brace 16 is also provided with a turnbuckle or other suitable tensioning device 22.

65 It will be seen from the foregoing that the gate is securely braced by the members 15 and 16, and prevented from sagging. The connection of the inner end of the brace 15 is with the post 12, so that the weight 70 of the gate is taken off the hinges 13, and as said connection is pivoted it swings freely with the gate when the latter opens or closes.

75 I claim:—

The combination with a gate and a post to which it is hinged, of a strut rising from the top of the gate intermediate its ends, tensioning members connected to the strut and extending in opposite directions therefrom, one of said members being anchored to the forward end of the gate, a bracket member supported by the post, a pivot pin carried by the bracket member independent of and in alinement with the axis of the 80 gate hinge, and a hinge member mounted on the pivot pin to turn thereon, to which member the other tensioning member is connected.

85 In testimony whereof I affix my signature. 90

ARTHUR W. KROON.
